UNITED STATES PATENT OFFICE.

ALEXANDER T. KASLEY, OF ESSINGTON, PENNSYLVANIA, ASSIGNOR TO WESTINGHOUSE ELECTRIC AND MANUFACTURING COMPANY, A CORPORATION OF PENNSYLVANIA.

DIAGONAL STRUT FOR LOCOMOTIVES.

Application filed January 26, 1923. Serial No. 615,119.

My invention relates to railway vehicle trucks and particularly to connecting means therefor which will safely restrict freedom of articulation between the respective truck members constituting the body support, and it has for an object to provide a connecting means of the character designated whereby excessive strains are prevented, and side thrusts of the wheels on the rails, together with the resultant wear incident thereto, are appreciably reduced while traversing curved sections of track.

It has for a further object to provide a connecting means which shall be rigid under most conditions of operation but flexible under extreme conditions of operation, and it has for a still further object the provision of a connecting means which will be automatically severed when the conditions of operation are of such extreme character as will tend to stress the connecting means beyond the limit of its flexibility.

These and other objects of my invention, which will be manifest in the further description thereof, are set forth in the following specification and illustrated in the accompanying drawing in which Fig. 1 is a view in elevation of an electric locomotive having two articulated trucks of six wheels each; Fig. 2 is a plan view of a pair of trucks having connecting means of the character disclosed in my invention, Fig. 3 is an enlarged plan view of the connecting means shown in Fig. 2; Fig. 4 is a plan view of another embodiment of my invention; Fig. 5 is a view, in elevation, of the intermediate connecting link; Fig. 6 is a sectional view in elevation taken on the line VI—VI of Fig. 3 and Fig. 7 is a sectional view in elevation taken on the line VII—VII of Fig. 4.

Railway vehicles employing multi-wheel trucks, as for example, those having two trucks of six wheels each coupled with a longitudinally-disposed link pivotally connected thereto, when traversing curved sections of track, develop a side thrust between the wheel flanges and the rails, resulting in wear thereof. Under extreme conditions of operation, this side thrust results at times in derailment of the vehicle or a prying loose of a portion of the rail.

The rear wheel in the front truck has been found by trial to run against the inner rail of the curve (unless the speed is very high

when centrifugal force throws it against the outer rail), while the front wheel of the rear truck runs against the outer rail. If the adjacent ends of trucks are connected together, the rear wheel of the front truck will usually be drawn away from the rail and the pressure on the flange of the front wheel of the rear truck consequently reduced.

Freedom of lateral movement has, in some instances, been eliminated by the installation of a rigid transverse link pivotally connected to diagonally-disposed adjacent corners of the trucks. Due to distortions of the track however, which may in some instances considerably increase the degree of curvature, or to misalignment in adjacent track sections, or to reverse curves, the vehicle may be compelled to traverse portions of track having an abnormally high degree of curvature. Under these extreme conditions, a rigid transverse connecting link designed for most operating conditions may either distort or destroy the track, the truck, or itself.

By my invention, I provide a transverse link connecting diagonally-disposed adjacent corners of the trucks, which link is rigid for most conditions of operation and flexible for extreme conditions of operation, thereby preventing or resisting freedom of relative lateral movement between the trucks and exerting a deciding guiding action thereon at all times.

Referring to the drawing for a more detailed description of my invention, in Fig. 2 I have indicated a pair of trucks 10 and 11 having the usual side frames 12 and 13 which are journaled to a plurality of axles 14 engaging wheels 15 in the usual manner. The trucks may be connected to a vehicle frame by center pins (not shown) which are movable longitudinally or transversely to permit chording of the vehicle on curves. The coupling or connecting means between trucks is as shown to a larger scale in Fig. 3 in which 16 and 17 are the adjacent ends of trucks 10 and 11, respectively. The ends of the trucks 10 and 11 are provided with centrally disposed openings 18 and 20 freely engaging coupling pins 19 and 21 to which are pivotally connected a link or draw bar 22. The side frames 12 and 13 of the trucks 10 and 11, respectively, have extending portions 23 reinforced by braces 24 and 25 which are secured to the end members 16 and 17.

and 17. The extending portions 23 are connected transversely by a link mechanism composed of flexible end members 26 and a centrally disposed rigid member 27. The two flexible end members 26, which are of similar construction, have partial links of fork formation 28, provided with two projecting elements 29 and 30 extending inwardly. The outer portions of the partial links 28 are secured at 32 to the extending portions 23, and the inner portions or projecting elements 29 and 30 freely engage spring retainer elements 33 and 34, which are of a circular conformation as shown in Fig. 6. A second partial link member 35 passes through and freely engages the spring retainer elements 33 and 34 and has an enlarged end portion 36 extending inwardly. Interposed between the retainer elements 33 and 34 is a spring 37 installed with an initial compression which is maintained by stop members 38, 39, 40 and 41, secured to their respective link members. Stop members 42 are provided on the partial link members 35 to prevent an excessive compressing of the springs.

The flexible end members are pivotally connected to the respective ends of the centrally-disposed rigid member 27 through the enlarged end portions 36 of the partial links 35. As shown, the rigid member 27 is inclined with respect to the flexible end members 26, and is preferably so constructed and disposed that lines joining the pivots 43 and the coupling pins 19 and 21 are substantially normal to the longitudinal axis of the trucks. As shown in Fig. 5, the member 27 is composed of two elements 44 and 45 connected by a plurality of rivets and 46. In order to maintain the longitudinal axes of the flexible end members 26 in a position substantially parallel to the transverse axes of the trucks, tie members 47 are provided, having one end 48 pivotally connected to the end members 16 or 17 and the other end 49 pivotally connected to the enlarged portions 36 of the partial links 35.

Having thus described the arrangement of an apparatus embodying one form of my invention, the operation thereof is as follows: Assuming the trucks 10 and 11 to be traversing a section of track having a normal curvature, the trucks articulate about the coupling pins 19 and 21. Any transverse relative movement between the adjacent ends of said trucks is resisted by the transverse link mechanism acting as a rigid connection, due to the springs 37 being maintained under sufficient initial compression. This transverse link mechanism, therefore, exerts a decided guiding action on the trucks, thereby considerably reducing the side thrust of the wheels on the rail.

Should the trucks 10 and 11 be compelled to traverse a section of track having an ab-

normal curvature, a slight amount of relative lateral movement between the trucks is necessary and the strain incurred in the transverse link mechanism becomes greater than the initial compressive strength of the springs 37. Full or free lateral movement is therefore resisted by the transverse link mechanism acting as a flexible connection, which lateral movement may involve either a decrease or an increase of the distance between the extension portions 23 of the trucks. In case of a decrease, the partial links 28 being free to move in the retainers 33 and 34 exert through the stops 39 inwardly extending thrusts upon the retainers 33 which move inwardly and compress the springs 37. The partial links 35, which are also free to move in the retainers 33 and 34, engage the retainers 34 through the stops 40 and exert a counterthrust thereon in an opposing direction. The springs 37 are therefore compressed an amount proportionate to the difference in strains between their initial compression and that prevailing in the link mechanism. The retainers 34 maintain their original relative position with the exception of a slight movement due to the angular displacement of the centrally-disposed connecting member 27.

Should the lateral distance between the trucks increase however, the partial links 28, being free to move in the retainers 33 and 34, exert through the stops 41 an outwardly-extending thrust upon the retainers 34, which move outwardly and compress the springs 37. The partial links 35, which are free to move in the retainers 33 and 34, engage the retainers 33 through the stops 38 and maintain them in substantially their original relative positions.

Should the operating conditions reach such extremes as to require a very unusual relative transverse movement between the trucks due, for example, to a derailment, the centrally-disposed rigid member 27 will fail by rivet shear upon a maximum change in length of the transverse link mechanism as permitted by the stop members 42. The rigid member is composed of two elements 44 and 45 connected by a plurality of rivets 46, the aggregate shearing value of which will insure failure of the same upon transmission of a predetermined strain.

Referring to Fig. 4 for another embodiment of my invention, I have indicated the two trucks 10 and 11 having adjacent ends 16 and 17 connected by the longitudinally-disposed link or draw bar 22 in a manner similar to that shown and described in reference to Fig. 3. The side frames of trucks 10 and 11 have extending portions 23 reinforced by braces 24 and 25 which are connected to the end members 16 and 17, respectively. The extending portions 23 are connected transversely by a link mechanism

composed of two flexible end members 59 and a centrally-disposed rigid member 60. The two flexible end members 59, which are similar in construction, consist of a partial link 5 of fork formation 62, having inwardly extending elements 63 and 64, and connected at its outer portion 65 to extending portions 23, of the truck frames. The extending elements 63 and 64 freely engage the spring retainer elements 66 and 67, which spring retainer elements are shown in plan in Fig. 7. A second partial link member 68 also of a fork formation, but having its major axis normally disposed with respect to the major axis of the partial link 62, is pivotally connected at its inner end 71 to the centrally-disposed rigid member 60, and has its projecting elements 69 and 70 extending outwardly and movably engaging the spring retainer elements 66 and 67. Interposed between the retainer elements 66 and 67 are springs 72 and 73 installed with an initial compression which is maintained by the stops 74, 75, 76 and 77, disposed on opposite sides of the retainer elements and secured to their respective partial link members. Stop members 78 are provided on the partial link members 68 to prevent an excessive compressing of the springs. The disposition and construction of the centrally-disposed rigid member 60 and the tie members 79 are similar to that shown and described with respect to Figs. 3 and 5.

The operation of this embodiment of my invention under normal operating conditions is similar to that enumerated with respect to Fig. 3, in that the transverse link mechanism acts as a rigid member while the trucks 10 and 11 are traversing a section of track having a normal degree of curvature. Should the trucks 10 and 11 be compelled to traverse a section of track having an abnormal degree of curvature, a slight amount of relative lateral movement between the adjacent ends of said trucks becomes necessary, and the strain transmitted by the transverse link mechanism becomes greater than the combined compressive strength of the springs 72 and 73. Full or free lateral movement is therefore resisted by the transverse link mechanism acting as a flexible connection, which movement may involve either a decrease or increase of the distance between the extending portions 23 of the trucks.

In case of a decrease, the partial links 62 exert through the stops 74 an inwardly-extending thrust upon the retainers 66 which move inwardly and compress the springs 72 and 73. The partial links 68, which are also free to move in the retainers 66 and 67, engage the retainers 67 and exert through the stops 77 a counter-force thereon in an opposite direction. The springs 72 and 73 are therefore compressed an amount proportion-

ate to the difference between their initial pressure and the stress prevailing in the link mechanism. The spring retainer 67 retains its original relative position with the exception of a slight movement due to the angular displacement of the intermediate connecting member 60.

Should the lateral distance between the trucks increase however, the partial links 62, being free to move in the spring retainers 66 and 67 exert through the stops 76 an outwardly-extending thrust upon the retainers 67, which move outwardly and compress the springs 72 and 73. The partial links 68, which are also free to move in the spring 80 retainers 66 and 67, engage the retainers 66 through the stops 75 and maintain them in substantially their original relative position.

Should the operating conditions reach such extremes as would require a transverse 85 relative movement between the adjacent ends of the trucks in excess of that permitted by the flexible end members, the centrally-disposed rigid member 60 would fail as has been heretofore described. While I have 90 utilized but two or four springs in my embodiments, I may employ any number or combination of springs or any suitable resilient means necessary to acquire a potential strength which will successfully resist 95 any tendency towards free relative movement by the adjacent ends of the trucks.

While I have shown my invention in but two forms, it will be obvious to those skilled in the art that it is not so limited, but is 100 susceptible of various other changes and modifications without departing from the spirit thereof, and I desire, therefore, that only such limitations shall be placed thereupon as are imposed by the prior art or as 105 are specifically set forth in the appended claims.

What I claim is:

1. In a railway vehicle, the combination with a pair of trucks, of a transverse link mechanism connecting diagonally disposed adjacent corners of the trucks, said mechanism comprising flexible and rigid members, said flexible members being under an initial load and said rigid members being 110 sufficiently weaker than the trucks to protect the latter against breakage in case of abnormal loads.

2. In a railway vehicle having articulated trucks, a hinge comprising a longitudinally 120 disposed link connecting said trucks, and a transverse link mechanism connecting the adjacent ends of said trucks at opposite sides, said transverse link mechanism having a constant effective length under all normal conditions of operation of the vehicle and having flexible means for permitting a variation in the effective length of the link mechanism upon it being subjected to abnormal loads.

3. In a railway vehicle having articulated trucks, a hinge comprising a longitudinally disposed link connecting said trucks, and a transverse link mechanism connecting the adjacent ends of said trucks at opposite sides, said transverse link mechanism comprising a flexible portion under an initial load and a rigid portion, said flexible portion permitting a variation in effective length of the link mechanism upon it being subjected to abnormal loads, and said rigid portion having such physical proportions as will permit a severing of the same upon an additional variation in the effective length of the transverse link mechanism.

4. In a railway vehicle, the combination with a pair of trucks, of a transverse link mechanism connecting diagonally disposed adjacent corners of the trucks, said link mechanism being composed of flexible and rigid link members, said rigid member having two elements secured to each other by a plurality of rivets, the aggregate strength of which will insure failure of the same upon transmission of a predetermined load by the link mechanism.

5. In a railway vehicle having articulated trucks, a longitudinally disposed link connecting said trucks, and a transverse link mechanism connecting diagonally disposed adjacent corners of the trucks, said transverse link mechanism having spring means disposed under such initial load that said transverse link mechanism has a constant effective length when transmitting normal loads and a variable effective length when transmitting abnormal loads.

6. In a railway vehicle having articulated trucks, a longitudinally disposed link connecting said truck, and a transverse link mechanism connecting diagonally disposed adjacent corners of the trucks, said transverse link mechanism having a plurality of springs disposed under such initial compression that any relative lateral movement between said trucks involving a transmission of strains less than the compressive strength of said springs is prevented, and any relative lateral movement involving the transmission of strains in excess of the initial compressive strength of said springs is permitted.

7. In a railway vehicle having articulated

trucks, a longitudinally disposed link connecting said trucks, means connecting diagonally disposed adjacent corners of the trucks, said means comprising a partial link carrying space retainers and secured at one end to the truck, stop members provided on the link to limit the distance to which said retainers may be spaced, a second partial link member associated by suitable mechanism to the diagonally opposite corners of the second truck, said link member passing through said retainer elements and provided with stop members spaced at a distance equal to the distance between the stop members of the first-named mechanism, and a spring under compression engaging said retainer members and holding them against the stop members, whereby for strains less than the initial force of compression of said spring, the said connecting means rigidly connect the said diagonally disposed corners of the trucks and for strains exceeding the compressive force of said springs the connecting means is permitted to vary its effective length.

8. In a railway vehicle having articulated trucks, a longitudinally disposed link connecting said trucks, means connecting diagonally disposed adjacent corners of the trucks, said means comprising a series of inter-connected rigid and flexible links, each of said rigid links comprising two elements having connecting means, said connecting means having such relative strength as will permit a parting of the elements upon the transmission of a predetermined strain, each of said flexible links having a partial link member carrying space retainers and stop members to limit the distance to which said retainers may be spaced and a second partial link member passing through said retainer elements and provided with stop members spaced at a distance equal to the distance between the stop members of the first-mentioned link member, and a spring under compression engaging said retainer members and holding them against said stop members.

In testimony whereof, I have hereunto subscribed my name this 23rd day of January 1923.

ALEXANDER T. KASLEY.
